Primary Examiner — Sheryl Lane*Assistant Examiner* — Samantha N Wood(74) *Attorney, Agent, or Firm* — Taft Stettinius & Hollister LLP(57) **CLAIM**

The ornamental design for a watch, as shown and described.

DESCRIPTION

FIG. 1 is a front elevational view of a watch showing our new design;

FIG. 2 is a back elevational view thereof;

FIG. 3 is a right side elevational view thereof;

FIG. 4 is a left side elevational view thereof;

FIG. 5 is a bottom plan view thereof;

FIG. 6 is a top plan view thereof; and,

FIG. 7 is a front, right side perspective view thereof.

The broken lines are included for the purpose of illustrating the environmental structure and form no part of the claimed design.

1 Claim, 7 Drawing Sheets(56)
